(52) **U.S. Cl.**

CLAIM

USPC **D23/366**

The ornamental design for a dispenser housing, as shown and described.

(58) **Field of Classification Search**

DESCRIPTION

USPC ..... 1/355-369; 261/DIG. 17, DIG. 42,
261/DIG. 65, DIG. 88, DIG. 89; D28/5, 6;
392/386, 390, 394, 395; 239/34, 44,
239/53, 55, 56, 326; D26/14, 17, 98, 9, 22,
D26/24; D11/131.1; D7/509, 522, 524, 537;
D23/355-369; 33/355-369

FIG. 1 is an isometric view of a top, front, and left side of an ornamental design for a dispenser housing;
FIG. 2 is a front elevational view of the housing of FIG. 1;
FIG. 3 is a rear elevational view of the housing of FIG. 1;
FIG. 4 is a left side elevational view of the housing of FIG. 1;
FIG. 5 is a right side elevational view of the housing of FIG. 1;

See application file for complete search history.

FIG. 6 is a top plan view of the housing of FIG. 1; and,
FIG. 7 is a bottom plan view of the housing of FIG. 1.
The dash-dash-dash broken lines are for the purpose of
illustrating environmental structure and form no part of the
claimed design.
